(57) **CLAIM**

The ornamental design for a modular component for a collector device, as shown and described.

DESCRIPTION

FIG. 1 is a perspective front view of a modular component for a collector device.

FIG. 2 is a front view of the modular component of FIG. 1. FIG. 3 is a rear view of the modular component of FIG. 1. FIG. 4 is a left side view of the modular component of FIG. 1.

FIG. 5 is a right side view of the modular component of FIG. 1.

FIG. 6 is a top view of the modular component of FIG. 1; and,

FIG. 7 is a bottom view of the modular component of FIG. 1.

The broken lines form no part of the claimed design.
